INVENTOR.

Eugene J. Ray

UNITED STATES PATENT OFFICE.

EUGENE J. RAY, OF BEVERLY, MASSACHUSETTS, ASSIGNOR TO UNITED SHOE MACHINERY CORPORATION, OF PATERSON, NEW JERSEY, A CORPORATION OF NEW JERSEY.

SKIVING MACHINE.

Application filed July 23, 1921. Serial No. 487,156.

To all whom it may concern:

Be it known that I, EUGENE J. RAY, a citizen of the United States, residing at Beverly, in the county of Essex and State of Massachusetts, have invented certain Improvements in Skiving Machines, of which the following description, in connection with the accompanying drawings, is a specification, like reference characters on the drawings indicating like parts in the several figures.

This invention relates to skiving machines and is herein illustrated as embodied in a machine of the type having cylindrical knives.

Such machines commonly comprise a cylindrical knife, a feed roll, usually located within the knife, an edge gage, and a presser which may, as in the case of the illustrative machine, take the form of a driven roll. The driven presser roll construction is used principally for skiving the edges of comparatively stiff pieces of work the convex curves of the edges of which are gradual rather than sharp. Nevertheless, considerable difficulty has been experienced with such machines and work because the edge of the work has not been automatically held against the edge gage with the result that considerable guiding of the work by the operator has been necessary.

One object of the present invention is to provide a construction, in a machine of this kind, which will feed box toes and similar pieces through the machine with the minimum of guiding effort on the part of the operator or with no guiding effort at all.

Other objects of the invention are to provide an improved construction, mounting and adjustment of the presser roll to vary the angle of the scarf produced while still maintaining a straight or flat scarf on the margin of the work.

Referring now to the accompanying drawings,—

Fig. 1 is a side elevation of a machine in which the present invention is embodied, and

Fig. 2 is an end elevation of the machine. In a general way the illustrative machine is or may be similar to the machine shown in Patent No. 1,117,541; and before proceeding to describe the improved parts, a general description of the old construction will be given. The machine of the present applica-

tion, like that of the patent, comprises a hollow base 3, the upper forward portion of which is formed as a work support or table 5 over which the work is presented and fed in the general direction indicated by the arrow in Fig. 1. A cylindrical knife 7 projects up through the top of the base of the machine in position to engage the work; and the work is fed to the knife by a feed roll 9, the work being held down upon the feed roll by a presser which, in the illustrative machine, is a roll 11 whereas in the patented machine a stationary presser foot is employed. The knife is mounted on the end of a drive shaft 13 which is rotated from any suitable source of power through a pulley on that shaft. The feed roll 9 is yieldingly supported in such manner that it may both yield away from the edge of the knife and tilt about an axis which is at right angles to its axis of rotation: it is driven from the knife shaft through a belt and suitable gearing. The mounting and driving connections of the feed roll 9 have not been shown since they are or may be like those of the patented machine. An edge gage 17 (see Fig. 2) is provided for engaging the edge of the work, said edge gage being adjustable as in the patented machine in a direction parallel to the axis of the feed roll. The presser roll 11 is carried in a manner presently to be described by a block 19 which is vertically slidable in the end of an overhanging arm 21, being urged upwardly at all times by a spring 23 as far as is permitted by an adjusting screw 25. This block 19 has a ribbed upper end as shown in Fig. 1 which is of greater thickness than the lower portion of the block. The ribbed end just fits in the socket in the head of the machine and serves as a floating pivot about which the lower end of the block may be swung. A small spring, not shown, acts upon the left-hand side of the block as viewed in Fig. 1 to hold the block against the end of an adjusting screw 50 provided with a lock nut 52. By turning the adjusting screw the block, and with it the presser member, may be adjusted backward and forward in the line of the feed of the work to bring the presser member into proper relation, in that line, to the knife. The machine, as thus far described, with the exception of the presser roll is or may be similar to the patented machine; and refer-

ence is made to the patent for details of construction. It will be understood, however, that the work is seized by the feed and presser rolls and advanced to the knife.

5 When the margin of a heavy piece of work such as a box toe is to be skived, it is desirable to substitute for the stationary presser foot of the patented machine a driven roll; and, in order to permit the angle of the 10 scarf to be varied, this roll is made adjustable. The construction should also be such that the work will require little or no guiding by the operator. Referring now more 15 particularly to Fig. 2, the presser roll 11 is large at that end adjacent the edge gage and small at the opposite end, the periphery of the roll being concavely curved longitudinally to correspond to the convex longitudinal curvature of the periphery of the 20 feed roll 9. The purpose of these complementary curves is to cause the production of a scarf which is straight or flat as distinguished from one which is curved or gouged out.

25 It is desirable, as has been stated, that the work be fed in as nearly an automatic manner as possible after once it has been properly presented to the machine. In other words, the edge of the work should remain 30 at all times in contact with the edge gage. It should neither be crowded against the edge gage too forcibly nor caused to leave the gage. In the illustrative machine the middle of the axis of the feed roll is indicated at 27, a vertical plane passed transversely of the roll through this point intersecting the periphery of the roll at approximately its largest diameter and consequently 35 in the zone in which the periphery is moving indicated at 27, a vertical plane passed transversely of the roll through this point intersecting the periphery of the roll at approximately its largest diameter and consequently in the zone in which the periphery is moving 40 faster than at the ends. The presser roll 11 is so located that a vertical plane A passed transversely of that roll through its larger end is substantially parallel to but spaced from the first-mentioned vertical plane. The 45 larger end of the presser roll, therefore, which is the faster moving end of that roll co-operates with the feed roll at a zone which is not traveling as fast as is the middle zone of the feed roll. With this construction and 50 relative location of the rolls it is found that the work will be fed properly through the machine with its edge in contact with the edge gage 17.

55 The spindle of the presser roll is rotatably mounted in a sleeve 29 which has integral with it an arm 31, said arm carrying at its upper end a segmental rack 33, the upper portion of this arm being provided with a segmental rib or projection 35 which rests 60 upon an arc-shaped ledge or guideway 37 formed at the lower end of the block 19. Meshing with the segmental rack 33 is a pinion 39. This pinion is fast to a shaft 41 which is rotatably mounted in the block 19, 65 said shaft having fast to it a small hand-

wheel 43 by which the shaft and pinion may be rotated to change the angular position of the sleeve 29 and consequently of the presser roll 11. In order to lock the shaft 41 of the pinion 39 in adjusted position, a plate 45, 70 which closes the cavity in the block 19 in which the pinion 39 is mounted, is engaged by the stem of a lock-nut 47 which is threaded on the end of the shaft 41. With this construction it will be clear that by loosening the lock-nut 47 and turning the hand-wheel 43, the presser roll 11 may be adjusted angularly. This adjustment takes place about a point or axis 49 which is in or intersects the 75 axis of the presser roll 7 and also lies substantially in the vertical plane A, the center of curvature of the arc-shaped ledge on which the segmental rack 33 bears being the point or axis 49.

80 In order to drive the presser roll 11 in its various adjusted positions, one end of the stem of this roll is enlarged and provided with a socket to receive a ball on the end of a link 51. The other end of the link has a similar ball which is received in a socket in 85 one end of a shaft 53 to the other end of which is fast a pulley 55. A belt 57 passes around this pulley and around a pulley 59 on one end of a shaft 61. The other end of this latter shaft carries a bevel gear 63 which 90 meshes with a bevel pinion 65 on one end of a shaft 67 the other end of which carries a pulley 69, said pulley being connected by a belt 71 with a pulley 73 fast to or rigid with a pulley 15 driven by a belt 54 from a pulley 95 56 on the shaft 13.

Having thus described my invention, what I claim as new and desire to secure by Letters Patent of the United States is:

1. A machine of the class described, having in combination, a rotary cylindrical knife, a rotary feed roll having a periphery which is convex longitudinally of the roll, a rotary presser roll having a large end and a small end, the periphery of the presser roll being concave longitudinally to correspond to the convex longitudinal curvature of the periphery of the feed roll, the large end of the presser roll being located above the feed roll and at one side of a vertical plane passed transversely through the center of the feed roll and having its smaller end extending over the smaller end of the feed roll, an edge gage located adjacent the larger end of the presser roll, and means for driving the 115 presser roll.

2. A machine of the class described, having in combination, a rotary cylindrical knife, a rotary feed roll having a periphery which is convex longitudinally of the roll, a 120 rotary presser roll having a large end and a small end, the periphery of the presser roll being concave longitudinally to correspond to the convex longitudinal curvature of the periphery of the feed roll, the large end of the 125 presser roll.

the presser roll being located above the feed roll and at one side of a vertical plane passed transversely through the center of the feed roll, an edge gage located adjacent to the larger end of the presser roll, means whereby the presser roll may be adjusted about a point lying within said roll and near the larger end thereof, and means for driving the presser roll.

3. A machine of the class described, having in combination, a rotary cylindrical knife, a rotary feed roll having a periphery which is convex longitudinally of the roll, a rotary presser roll having a large end and a small end, the periphery of the presser roll being concave longitudinally to correspond to the convex longitudinal curvature of the periphery of the feed roll the large end of the presser roll being located above the feed roll and at one side of a vertical plane passed transversely through the center of the feed roll, an edge gage located adjacent to the larger end of the presser roll, means whereby the presser roll may be adjusted about a point lying substantially in the axis of said roll and near the larger end thereof and means for driving the presser roll.

4. A machine of the class described, having in combination, a rotary cylindrical knife, a rotary feed roll having a periphery which is convex longitudinally of the roll, a rotary presser roll the periphery of which is concavely curved to correspond to the convex longitudinal curvature of the feed roll, said presser roll being larger at one end than at the other, means whereby the presser roll may be adjusted about a point within the roll at the larger end thereof, said point lying in a vertical plane which intersects the feed roll transversely at a locality between one end and the middle thereof and means for driving the presser roll.

5. A machine of the class described, having in combination, a rotary cylindrical knife, a rotary feed roll having a periphery which is convex longitudinally of the roll, a rotary presser roll the periphery of which is concavely curved to correspond to the convex longitudinal curvature of the feed roll, said presser roll being larger at one end than at the other, means whereby the presser roll

may be adjusted about a point lying substantially in the axis of the presser roll and means for driving the presser roll.

6. A machine of the class described, having in combination, a rotary cylindrical knife, a rotary feed roll the periphery of which is convex longitudinally of said roll, a presser roll having a periphery which is concave longitudinally to correspond to the convex longitudinal curvature of the feed roll, said presser roll being larger at one end than at the other, means whereby the presser roll may be adjusted angularly about a point within the roll at the larger end thereof, said means including a sleeve in which the spindle of the presser roll is rotatably mounted, a segmental rack rigid with the sleeve, and a pinion for moving the rack and means for driving the presser roll.

7. A machine of the class described, having in combination, a cylindrical knife, a rotary shaft upon which the knife is mounted, a rotary feed roll the periphery of which is convex longitudinally of said roll, a presser roll having a periphery which is concave longitudinally to correspond to the convex longitudinal curvature of the feed roll, said presser roll being larger at one end than at the other, means whereby the presser roll may be adjusted angularly to vary the angle of the scarf produced, and means including a belt for driving the presser roll from the knife shaft.

8. A machine of the class described having, in combination, a rotary cylindrical knife, a rotary feed roll the diameter of which is greater at the middle than at either end whereby the periphery is convex longitudinally of the roll, a presser roll having one end of greater diameter than the other, the end of greater diameter being located adjacent the portion of greatest diameter of the feed roll, means for positively driving the presser roll, and means whereby the presser roll may be adjusted angularly about a point lying substantially in its axis of rotation while maintaining the driving mechanism operative.

In testimony whereof I have signed my name to this specification.

EUGENE J. RAY.
